OTHER PUBLICATIONS

Product literature for the Patientline system (website prints and product photos). Not later than Sep., 2000. Eleven (11) sheets.

Product literature for Ackerman. Date Unknown. Seven (7) sheets. www.ackerman.com/clino/index.html.

Product literature for BedWeb. Date Unknown. Four (4) sheet.

Product literature for Ascom Nira. Date Unknown. One (1) sheet.

Product literature for Tyco. Date Unknown. One (1) sheet.

Product literature for Siemens. Date Unknown. One (1) sheet.

Product literature for HCIC+. Date Unknown. Three (3) sheets. www.hcic.com/products/television/index.htm.

Product literature for Kerfone. Date Unknow. Three (3) sheets. www.kerfone.co.uk/kerfone.htm.

(List continued on next page.)

Primary Examiner—Jeffrey Asch

(74) Attorney, Agent, or Firm—Clayton, Howarth & Cannon, P.C.

(57) **CLAIM**

I claim the ornamental design for a communication center, as shown and described.

DESCRIPTION

FIG. 1 is a perspective view thereof;

FIG. 2 is a top view thereof;

FIG. 3 is a bottom view thereof;

FIG. 4 is a rear view thereof;

FIG. 5 is a front view thereof;

FIG. 6 is a right side view thereof; and,

FIG. 7 is a left side view thereof.

1 Claim, 3 Drawing Sheets

OTHER PUBLICATIONS

Product literature for Schmelter. Date Unknown. Three (3) sheets. www.avm-schmelter.de/lcd.htm.
Photo of Zettler product. Date Unknown. One (1) sheet.
Product literature for Teleware. Date Unknown. One (1) sheet.

Photo of HTS product. Date Unknown. One (1) sheet.
Product literature for Wandsworth. Date Unknown. One (1) sheet. www.wandsworth-electrical.com/page99.htm.
Product literature for Static Systems Group. Date Unknown. One (1) sheet. www.staticsystems.co.uk.
